(57) **CLAIM**

The ornamental design for a tampon applicator barrel, as shown and described.

DESCRIPTION

FIG. 1 is a front perspective view of a tampon applicator barrel according to the present invention;

FIG. 2 is a rear perspective view of a tampon applicator barrel according to the present invention;

FIG. 3 is a top view of the tampon applicator barrel of FIG. 1;

FIG. 4 is the tampon applicator barrel of FIG. 3 rotated by 90 degrees about a longitudinal axis;

FIG. 5 is a front end view of the tampon applicator barrel of FIG. 1; and,

FIG. 6 is a rear end view of the tampon applicator barrel of FIG. 1.

The broken line showing is for illustrative purposes only and forms no part of the claimed design.
